UNITED STATES PATENT OFFICE.

ADAM C. WEST, OF BLANCHARD, MICHIGAN, ASSIGNOR OF TWO-THIRDS TO
CHARLES V. WEST, OF SAME PLACE.

PLOW.

SPECIFICATION forming part of Letters Patent No. 288,531, dated November 13, 1883.

Application filed August 14, 1883. (No model.)

To all whom it may concern.

Be it known that I, ADAM C. WEST, of Blanchard, in the county of Isabella and State of Michigan, have invented certain new and 5 useful Improvements in Plows, of which the following is a full, clear, and exact description.

This invention relates to the point of a plow, including the colter and share thereof, and is designed as an appendage or sheathing to the 10 cast-iron point of a plow, for the purpose of giving thereto good, durable steel edges, which may be sharpened as required. Such appendage not only adds to the durability of the point, causing it to last much longer than the 15 ordinary cast-iron one having no such attachment, but facilitates the work of plowing, and at the same time strengthens the point generally and relieves the plow of much weight.

To these and other ends my invention 20 consists in a detachable steel cap-point in the form of a hood or sheath, and which is separate from the share, over the forward end of which and point end of the plow it fits, together with a steel plate, forming the share 25 and colter, for application as a cover to the cast-iron point of a plow, substantially as hereinafter described.

Reference is to be had to the accompanying 30 drawings, forming part of this specification, in which similar letters of reference indicate corresponding parts in all the figures.

Figure 1 represents a perspective view of a 35 cast-iron plow-point having my invention applied. Fig. 2 is a perspective view of a combined share and colter plate forming part of the invention; Fig. 3, a perspective view of the cast-iron point detached; Fig. 4, a perspective view of a detachable steel cap-point, and Fig. 5 a vertical longitudinal section of 40 the same.

A is an ordinary cast-iron plow-point, of any 45 desired size and shape, according to the particular pattern of plow, and which may be secured to its place by bolts, locks, or other devices, as usual, or in any approved manner. This cast-iron point I cover, to give increased 50 strength, durability, and ease in the performance of its work, by an appendage or attachment, which may be applied by any blacksmith of ordinary skill, either to new plow-

points or to worn-out ones, at a comparatively small cost. Such is accomplished in part by applying to the point a steel covering-plate 55 cut and bent to form the share B and colter C, which may be of any desired shape; but the share B should be made to project over the right-hand wing of the point some one and a half inch, more or less, or sufficiently to give a good, lasting steel cutting-edge, that may be sharpened, if necessary. The whole may be 60 made from a plate mainly of triangular shape, except at its forward lip end, which lies under the detachable cap-point D; the left-hand portion of the plate being bent up to form the colter C, the front edge of which should be 65 sharpened. After the plate has been thus fashioned and prepared, it is fitted on the cast-iron point A, and may be secured by the same bolt which holds the cast point to the plow, the same first passing through the steel plate 70 at s, having a countersunk hole in it for the purpose, and by any number of rivets b, arranged to pass through both the steel plate and cast point, the heads of the rivets being countersunk in the plate. The steel-plate 75 cover to the point, forming share and colter, having been thus secured, the cap-point D is fitted over the lip end of the plate and forward end of the point. This cap-point is formed of a steel plate cut into suitable shape 80 and bent around and welded to form a hood or sheath to the forward end of the point, and having a piece of steel, c, welded in it at its front end, sufficiently large to provide for the cap-point being sharpened occasionally, or as 85 often as is necessary. I furthermore harden the solid point of the cap, to give it durability. Said cap-point may be inclined a little downward, or to the landside of the plow, as shown at d, as the general run of the plow may require. It is fitted on or over the plow-point by heating it and driving it on, and then allowing it to cool and contract thereon, the front solid end of it being more rapidly cooled, to 90 harden it. Thus fitted, said cap-point by 95 shrinking not only holds its position, but holds the front end of the share and colter plate.

As it is the forward end of the point of a plow which wears most rapidly, this separate and detachable steel cap piece or point is not 100 only more durable, but it may be readily sharpened, and removed when worn and be replaced

by another without disturbing the share and colter plate. The steel share and colter plate or point cover will also add materially to the durability of the point, and may be sharpened 5 or be removed and replaced by another, thus adding materially to the durability of the plow having a cast-iron point, besides reducing weight and easing the plow in its work.

This covering of the plow-point essentially 10 differs from other attached plow-points, which involve a peculiar construction of the plow, and which are attachments to the landside of the plow, or have the whole of one piece of metal, forming both point and share, attached 15 to the mold-board by socket and clasp, and which constitute the entire point, while in my case the attachment is an independent piece, and is held to the cast point by bolts and rivets.

I do not abandon or dedicate to the public

any patentable feature set forth herein and not 20 hereinafter claimed, but reserve the right to claim the same either in a reissue of any patent that may be granted upon this application or in other applications for Letters Patent that I may make.

Having thus described my invention, I claim 25 as new and desire to secure by Letters Patent—

The combination, with the cast-iron plow-point A, of a steel-plate covering thereto, constructed to form both the share B and colter 30 C, and the separate and detachable cap-point D, applied to the point and assisting to hold the share and colter in position, essentially as described.

ADAM CLARK WEST.
